CLAIM

The ornamental design for a filter sheet for a cell collecting cartridge, as shown and described.

DESCRIPTION

FIG. 1 is a front view of a first embodiment showing our new design;

FIG. 2 is a rear view thereof;

FIG. 3 is a top plan view thereof;
FIG. 4 is a bottom plan view thereof;
FIG. 5 is a right side view thereof;
FIG. 6 is a left side view thereof;
FIG. 7 is an enlarged partial view of FIG. 1;
FIG. 8 is a sectional view of FIG. 7;
FIG. 9 is another enlarged partial view of FIG. 1;
FIG. 10 is another enlarged partial view of FIG. 1;
FIG. 11 is a perspective view thereof, with the filter sheet for a cell collecting cartridge shown in an exploded environment;
FIG. 12 is a perspective view thereof, with the filter sheet for a cell collecting cartridge in another environment;
FIG. 13 is an enlarged view of an opening located in the filter sheet for a cell collecting cartridge;
FIG. 14 is another front view of the filter sheet for a cell collecting cartridge.
FIG. 15 is a front view of a second embodiment showing our new design;
FIG. 16 is a rear view thereof;
FIG. 17 is a top plan view thereof;
FIG. 18 is a bottom plan view thereof;
FIG. 19 is a right side view thereof;
FIG. 20 is an enlarged view of the 20-20 20-20 portion of FIG. 14;
FIG. 21 is a 21-21 sectional view of FIG. 20;
FIG. 22 is an enlarged view of the 22-22 22-22 portion of FIG. 14;
FIG. 23 is an enlarged view of the 22-22, 23-23 portion of FIG. 14;
FIG. 24 is an enlarged view of FIG. 15;
FIG. 25 is a perspective view thereof, with the filter sheet for a cell collecting cartridge shown in an exploded environment;
FIG. 26 is a perspective view thereof, with the filter sheet for a cell collecting cartridge in another environment;
FIG. 27 is an enlarged view of an opening located in the filter sheet for a cell collecting cartridge; and,
FIG. 28 is another front view of the filter sheet for a cell collecting cartridge.
In the drawings, the broken lines are for the purpose of illustrating environment only and form no part of the claimed design.
